CLAIM

The ornamental design for a "single site surgical uniport," as shown and described.

DESCRIPTION

This is a design application that claims the benefit of, U.S. patent application Ser. No. 12/220,248 filed on Jul. 23, 2008, now U.S. Pat. No. 9,011,319 issued Apr. 21, 2015, entitled "Conical Laparoscopic Apparatus for Minimally Invasive Surgery"; which is a continuation-in-part of U.S. patent application Ser. No. 11/710,388 filed on Feb. 23, 2007. The above application is commonly assigned with this National Stage application and is incorporated herein by reference in its entirety.

FIG. 1 is a front perspective view of the single site surgical uniport showing our new design;

FIG. 2 is a left side view thereof;

FIG. 3 is a right side view thereof;

FIG. 4 is a front side view thereof;

FIG. 5 is a back side view thereof;

FIG. 6 is a top plan view thereof; and,

FIG. 7 is a bottom plan view thereof.

The broken lines immediately adjacent the shaded areas represent the bounds of the claimed design while all other broken lines are directed to environment and are for illustrative purposes only; the broken lines form no part of the claimed design.
